Davis & Davis

UNITED STATES PATENT OFFICE.

HENRY D. CURTIS, OF RED BANK, NEW JERSEY.

HAT-SIZE-REDUCING DEVICE.

1,219,086.

Specification of Letters Patent. Patented Mar. 13, 1917.

Application filed November 1, 1916. Serial No. 128,838.

To all whom it may concern:

Be it known that I, HENRY D. CURTIS, a citizen of the United States, and resident of Red Bank, county of Monmouth, and 5 State of New Jersey, have invented certain new and useful Improvements in Hat-Size-Reducing Devices, of which the following is a specification.

This invention relates to improvements in 10 hat-size-reducing devices, and more particularly to that type of devices for reducing the size of hats disclosed in Letters Patent No. 949,264, granted February 15, 1910, to Robert H. Curtis and Henry D. Curtis.

15 The present invention has for one of its objects the provision of a device of the character set forth which may be easily and inexpensively manufactured.

A further important object is the provision of a size-reducing device which shall 20 be readily adapted for manufacture in various sizes and thicknesses.

Another object of the invention is the provision of a soft and yielding covering 25 for the resilient metal core.

In the accompanying drawings, Figure 1 is a vertical sectional view taken through a hat having the size-reducing device applied thereto;

30 Fig. 2 is a perspective view showing the device ready for application to a hat;

Fig. 3 is a detail perspective view showing the construction and manner of applying the yielding covering to the resilient 35 metal core; and

Fig. 4 is a vertical sectional view taken through the size-reducing device.

Referring to the drawings by numerals, 1 designates the crown of a hat, 2, the brim, 40 and 3 the sweat band thereof. The size-reducing device 4 is inserted and held within the hat between the crown 1 and the sweat band 3, so that the device is entirely concealed from view by the sweat band, as 45 shown in Fig. 1.

The reducing device 4 comprises a core or body portion 5 formed of a strip of thin flexible metal, or other flexible material. The core 5 is provided with a plurality of 50 prongs or spurs 6 at suitable intervals on one side thereof. The core is preferably formed of a strip of thin spring steel having the spurs 6 struck up therefrom.

The core 5 is entirely inclosed within a soft, yielding covering 7 of loosely woven or 55 knitted textile fabric, or open mesh fabric such as gauze, cheese cloth, mosquito netting or the like. This yielding covering is applied to the core by winding one or more narrow strips 8 of the fabric spirally around the core, as shown more clearly in Fig. 3 of the drawings. The ends of the spirally wound covering 7 are twisted and cemented as shown at 9 in Fig. 1. The twisting and 60 cementing of the ends of the covering prevents unwinding of the spirally wound strips 8 and also serves to prevent the protrusion of the ends of the core from the covering.

The prongs 6 readily pass through the 70 loosely woven or knitted strips of fabric 8 as the strips are wound upon the core. The spurs or prongs are made sufficiently long to project slightly beyond the outer surface of the completed covering so as to adapt 75 them to penetrate the crown of the hat when the device is placed in position for use and thus hold the device in proper position.

The spurs or prongs also serve to prevent longitudinal displacement of the several 80 wraps or spirals of the covering along the core in handling the device.

An important feature of the invention consists in forming the covering by winding narrow strips of open-mesh fabric, or knitted or loosely woven goods, spirally around the core. By this arrangement a highly yieldable covering of any desired thickness 85 may be readily applied to the core.

It will be observed that the core is entirely inclosed within the covering and that the spirally wound covering is securely held on the core, the twisted and cemented ends of the covering and the spurs coöperating to hold the covering in place.

95 What I claim is:

1. A size-reducing device for hats comprising a flexible metal core having spurs projecting from one side thereof, and a covering of pliable material surrounding said core, said covering being formed of a plurality of strips of material wound around said core and having the ends of the strips at each end of the core twisted and cemented together.

100 2. A size reducing device for hats com-

prising a flexible core having spurs and a covering of open-mesh fabric completely inclosing the core, said covering consisting of a plurality of strips of fabric wound one upon the other spirally around the core, the margins of the adjacent coils overlapping each other, the ends of the strips extending

beyond the ends of the core being twisted and cemented together to prevent unwinding of the strips.

10 In testimony whereof I hereunto affix my signature.

HENRY D. CURTIS.
